UNITED STATES PATENT OFFICE.

HALLEY C. DOLAN, OF DETROIT, MICHIGAN, ASSIGNOR OF ONE-HALF TO MALCOLM J. McLEOD, OF DETROIT, MICHIGAN.

PUSH-BUTTON.

1,216,553.

Specification of Letters Patent. Patented Feb. 20, 1917.

Application filed April 26, 1915. Serial No. 24,113.

To all whom it may concern:

Be it known that I, HALLEY C. DOLAN, a citizen of the United States of America, residing at Detroit, in the county of Wayne 5 and State of Michigan, have invented certain new and useful Improvements in Push-Buttons, of which the following is a specification, reference being had therein to the accompanying drawings.

10 This invention relates to push buttons, and more particularly to a multiple switch by which a plurality of electrical circuits can be easily controlled.

15 The primary object of my invention is to provide an electric switch in the form of a button which is tiltable in various directions to establish electric circuits, said switch having the contact pieces thereof compactly arranged whereby the device will resemble an 20 ordinary push button.

A further object of this invention is to provide a simple, durable and inexpensive switch for electrical circuits that can be advantageously used in connection with an 25 automobile traffic signal, the compactness of the switch permitting of its ready installation upon the steering wheel post of an automobile within easy reach of the chauffeur or operator.

30 The above and other objects are attained by a mechanical construction that will be hereinafter specifically described and then claimed, and reference will now be had to the drawing, wherein

35 Figure 1 is a plan of the push button;

Fig. 2 is a side elevation of the same;

Fig. 3 is a cross sectional view of the push button, and

Fig. 4 is a plan of the same with the cover 40 thereof removed and illustrating electrical circuits in connection with the button.

A push button in accordance with this invention comprises a base plate 1 made of light and durable metal and circular in 45 plan. Mounted upon this base plate is a disk 2 made of fiber or a suitable insulation material. The disk 2 is of less diameter than the base plate 1, thereby affording a seat upon the edges of the base plate 1 for a 50 cover 3 provided with inwardly projecting apertured lugs 4 receiving the screw 5 or other fastening means employed for retaining the cover upon the base plate.

The disk insulation 2 has a central open-

ing 6 providing clearance for a yieldable or 55 resilient post 7. The yieldable post 7 is made of coiled wire with the convolutions thereof closely assembled and the lowermost convolution connected to a rivet 8 or other fastening means employed for attaching the 60 lower end of the post to the base plate 1; also to the strap 9 of a conventional form of clamping device 10 by which the button or switch can be attached to a steering post, a part thereof or any suitable support. 65 Connected to the upper convolution of the post and inclosing the uppermost convolution is an inverted conical shaped head 11 provided with a button or finger piece 12 extending through an opening 13 provided 70 therefor in the cover 3. The walls of the opening 13 are scalloped or recessed, as at 14 to permit of the button or finger piece 12 being tilted or swung to one side or the other, for a purpose that will hereinafter 75 appear.

The conical shaped head 11 is provided with a metallic contact member 15 which practically incloses the head and is in contact with the post 7. The contact member 80 15 is adapted to engage contact 16 carried by arms 17 connected to the disk of insulation 2 by binding screws or posts 18. The contacts 16 are spaced apart in proximity to the post 7 and each contact has a head 19 85 seated in the disk 2, the heads of said contacts preventing the same from becoming accidentally displaced relative to the disk. The screws or posts 18 are in proximity to openings 20 in the disk 2 and the base plate 90 1, whereby leading in wires 21 can be connected to the screws or binding posts 18.

With the contact member 15 disposed above and equidistant from the contacts 16, the button or finger piece 12 can be easily 95 manipulated to tilt the member 15 in a desired direction whereby it will contact with one of the contacts 16. As an instance of the use of the button or switch, there is diagrammatically illustrated electrical devices, 100 as solenoids or electro-magnets 22 and an electric automobile horn 23 all of which are in circuit with a suitable source of electrical energy, as battery cells 24, the ground and the contacts 16. The yieldable post 7 and consequently the contact member 15 is 105 grounded through the medium of the clamping device 10 and to facilitate the use of a

- button or switch in connection with an automobile traffic signal utilizing the horn 23 and the solenoids or electro-magnets 22, the top of the cover 3 is provided with indicia 5 for audible or visible signals. As shown in Fig. 1, the top of the cover 3 has the character "H" indicating the horn 23, and the characters "L," "R" and "S" indicating "Left," "Right" and "Slow" respectively.
- 10 When the button or finger piece 12 is tilted toward the character "L" or to the "left" an electric circuit is immediately established in one of the solenoids or electro-magnets which is adapted to operate a visible signal 15 and this circuit is completed by the contact member 15 engaging one of the contacts 16.
- The closely wound spring constituting the post 7 possesses sufficient rigidity to maintain the button or finger piece 12 in an up- 20 right position centrally of the cover 3 and normally out of engagement with the contacts 16, yet the post possesses sufficient resiliency to permit of the finger piece or button 12 being swung to one side, tilting the 25 post 7 and placing the contact member 15 in engagement with one of the contacts 16. When the finger piece of button 12 is released the post 7 immediately restores the button or finger piece to its normal position 30 concentric of the circular casing formed by the base plate 1 and the cover 3.

Any suitable means, as screws 25 can be employed for connecting the disk 2 to the plate 1, and by removing the cover 3, easy

access is had to the screws or binding posts 35 18 for making electrical connection.

One embodiment of my invention has been illustrated but it is to be understood that the structural elements are susceptible to such changes as fall within the scope of 40 the appended claim.

What I claim is:—

A coiled spring circuit closer comprising a base plate, a disk of insulation on said base plate of less diameter than said base 45 plate, a casing seated on the edge of said base plate around said disk, contacts on said disk within said casing adapted to be included in electric circuits, a coiled spring within said casing having the lowermost 50 convolutions thereof in said disk of insulation and connected to said base plate and adapted for a circuit including either of said contacts, an inverted conical shaped contact member supported by the uppermost convolutions of said spring adapted to be brought into contact with either of said contacts by tilting the upper portion of said coiled spring, and a button carried by said contact member and protruding out of said 55 casing to facilitate tilting said spring.

In testimony whereof I affix my signature in presence of two witnesses.

HALLEY C. DOLAN.
